(57) **CLAIM**

The ornamental design for a case for lenses, as shown and described.

DESCRIPTION

FIG. 1 is a perspective view of our new design of the case for lenses viewed from the front and top direction without the inner pod fitted, showing the interior structure;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a view of our new design seen in FIG. 1 shown with the inner pod fitted;

FIG. 9 is a top view of FIG. 8;

FIG. 10 is a bottom view of FIG. 8;

FIG. 11 is a front view of FIG. 8;

FIG. 12 is a rear view of FIG. 8;

FIG. 13 is a right side view of FIG. 8; and,

FIG. 14 is a left side view of FIG. 8.

The broken lines in the drawings are used to illustrate unclaimed parts of the invention and form no part of the claimed design.

1 Claim, 14 Drawing Sheets
